UNITED STATES PATENT OFFICE

KINJIRO OKABE, OF SENDAI, JAPAN, ASSIGNOR TO GENERAL ELECTRIC COMPANY, A CORPORATION OF NEW YORK

OSCILLATION GENERATOR

Application filed June 13, 1928, Serial No. 285,008, and in Japan July 1, 1927.

My invention relates to high frequency oscillation generators, and it has for one of its objects to provide improved means for generating oscillations of ultra short wave 5 length.

Another object of the invention is to provide means for producing considerable amounts of power in the form of oscillations of ultra high frequency.

10 Still another object of the invention is to provide electron discharge apparatus of novel construction which is particularly adapted for use in connection with the production of high frequency oscillations.

15 In my Japanese Patent No. 75,255 I disclosed an ultra short wave oscillation generator comprising an electron discharge device in the form of a magnetron having a cylindrical anode, a cathode extending along 20 the axis of the anode cylinder and a connection between the cathode and the anode cylinder upon which high frequency oscillations were produced when the unidirectional magnetic field was adjusted at or above a certain 25 critical value.

My present invention is an improvement upon the invention disclosed in my former Japanese patent whereby a considerably greater amount of high frequency energy is 30 produced. This increase in energy results essentially from longitudinally slitting the anode cylinder into a plurality of segments arranged symmetrically around the cathode and connecting these segments through a 35 source of potential and conductors upon which the ultra short wave oscillations are produced to the cathode. I have found that by suitably adjusting these conductors that a circuit may be provided which is resonant 40 at the frequency of the oscillations produced thereby still further increasing the intensity of the high frequency oscillations.

The novel features which I believe to be characteristic of my present invention are 45 set forth with particularity in the appended claims. My invention itself, however, both as to its organization and method of operation together with further objects and advantages thereof may best be understood by reference to the following description taken in

connection with the accompanying drawings in which Fig. 1 represents an end view of the electron discharge device employed in connection with my invention; Fig. 2 represents a side view thereof; Fig. 3 represents a 55 modification; Fig. 4 represents a circuit arrangement which may be employed, and Fig. 5 represents a system of antennae for radiating oscillations produced by means such as that shown in Fig. 4.

60 Referring to the drawings the electron discharge apparatus which comprises an important part of my invention comprises a vessel containing a plurality of anodes P which are arranged upon opposite sides of a 65 cathode F extending through the vessel. These anodes are of curvilinear form and are symmetrically arranged with respect to the cathode to form segments of a cylinder, as shown in Figs. 3 and 4, the filament extending 70 along the axis of the cylinder.

These anode segments are connected together by means of conductors P', which as shown in Fig. 4 extend a suitable distance 75 outside of the vessel and are then joined together and connected to one of two parallel conductors W. One of the parallel conductors is connected to one side of the cathode and the other parallel conductor is connected through a source of anode potential to the 80 cathode. The two parallel conductors are also connected together at a suitable point by means of a short circuiting condenser C.

By means of a coil M which surrounds the vessel containing the anodes P and which 85 is energized with unidirectional current, a substantially uniform magnetic field is produced within the discharge device the lines of force of which extend parallel with the axis of the cylinder formed by the anodes P. 90

It has been found that with a certain high unidirectional potential applied to the anodes that if the field current is increased above a certain critical value that high frequency oscillations are produced upon the conductors 95 P' and W having a wave length of the order of a fraction of a meter. By adjusting the conductors P' as by adjusting the distance between the conductors at the point B, or by adjusting the point at which the condenser 100

C is connected between the conductors W, the external circuit may be made to resonate with the frequency of the oscillations produced and a considerable increase in the intensity 5 of oscillations produced upon the parallel conductors may be noted.

It has been found that a material increase in output energy results from splitting the anode in the manner indicated. While 10 conductors P' connect the anodes these conductors are of sufficient length to permit the anodes to operate separately. This length is such that this increase in output energy is noted and such that the external circuit may 15 be adjusted to resonate with the frequency of oscillations produced by adjusting the distance between the different conductors at the point B.

In Fig. 3 one of the cathode conductors is 20 shown as extending on the outside of the anode cylinder P, P. In case this conductor is extended into the parallel line W the intensity of the high frequency oscillations produced upon the parallel conductors may 25 be increased by increasing the capacity coupling to this conductor by attaching a plate member A thereto, as shown in the figure.

For the purpose of radiating oscillations of the type produced upon the parallel conductors the means shown in Fig. 5 may be employed. This means comprises oppositely 30 extending radiating conductors E each of which has a length equal to one-half of a wave length of the oscillations produced and 35 which are connected at the points upon the parallel conductors at which the potential loops of the standing wave occur. As thus arranged these conductors will radiate a space wave having the frequency of the oscillations 40 produced in a direction at right angles to the plane comprising the conductors E or, in other words, at right angles to the plane of the drawings. The length of the conductors E and the spacing of these conductors along 45 the parallel conductors has been indicated in Fig. 5, λ representing the wave length.

While I have shown a particular embodiment of my invention it will be understood by those skilled in the art that many changes 50 and modifications, both in the circuit arrangement and in the instrumentalities employed, may be made without departing from my invention, and I therefore aim in the appended claims to cover all such changes and 55 modifications as fall within the true spirit and scope of my invention.

What I claim as new and desire to secure by Letters Patent of the United States, is:—

1. The combination, in an oscillation generator, of an electron discharge device comprising a cathode, a plurality of plate-like anode members arranged around and substantially enclosing said cathode, means for producing a magnetic field between said members and parallel with said cathode, a con-

nexion between each of said members and said cathode including a source of potential and a connection between said members whereby high frequency oscillations are produced, said last connection being variable to affect the oscillations produced. 70

2. The combination, in an oscillation generator, of an electron discharge device comprising a cathode, a plurality of plate-like anode members arranged symmetrically around and substantially enclosing said cathode, a connection between said anode members, means connected between said cathode and connection for impressing a positive potential on said anode members, means for producing unidirectional magnetic field between said members and parallel with said cathode whereby high frequency oscillations are produced, said connection being adjustable to provide a resonant circuit at the frequency of 85 oscillations produced. 80

3. In a high frequency oscillation generator, an electron discharge device having an anode structure in the form of a cylinder, said cylinder being longitudinally slitted to 90 form a pair of separate oppositely disposed anode segments, an electron emitting cathode extending along the axis of said cylinder, means for producing a substantially uniform unidirectional magnetic field parallel with 95 said cathode, an adjustable connection between said anodes for varying the output from said generator, and means connected between said connection and said cathode for impressing a positive potential upon said 100 anodes. 100

4. In a high frequency oscillation generator, an electron discharge device having an anode structure in the form of a cylinder, said cylinder being longitudinally slitted to 105 form a pair of separate oppositely disposed anode segments, a cathode extending along the axis of said cylinder, means for producing a substantially uniform unidirectional magnetic field parallel with said cathode, an 110 adjustable connection between said anodes, means for impressing an electromotive force between said cathode and connection, a pair of parallel conductors extending from said connection and cathode, a connection for 115 high frequency currents between said conductors and a radiating system connected to said conductors. 115

5. The combination, in an oscillation generator, of an electron discharge device comprising a cathode, a plurality of plate-like anode members arranged around and substantially enclosing said cathode, means for producing a magnetic field between said members and parallel with said cathode, a connection between said anode members, means for impressing positive potential on said anode members and an adjustable connection between said last connection and said cathode 120 125 130

whereby a circuit resonant at the frequency of oscillations produced is provided.

6. An electron discharge device including an envelope, a cathode adapted to emit electrons extending within said envelope, an anode structure within said envelope comprising a plurality of plate-like members extending adjacent said cathode, conductors connected respectively to said anode members and connected to each other external to said envelope, and means for producing a magnetic field in the space between said cathode and anode members.

In testimony whereof I have fixed my signature.

KINJIRO OKABE.
